York

Application June 17, 1937, Serial No. 148,634

2 Claims. (Cl. 176—122)

This invention relates to glow lamps for use in recording sound on or reproducing sound from a photographic sound record and particularly to a glow lamp for use with a film which is adapted to contain a plurality of spaced parallel sound record tracks.

An object of the invention is to provide a glow lamp which is adapted to project a light of equal intensity across the entire active area of the film so that the various sound record tracks can be scanned without shifting the position of the lamp.

Another object of the invention is to provide a glow lamp of simple and sturdy construction in which the light is efficiently utilized.

Another object is to provide a scanning system in which the scanning ray can be shifted from one sound record track to the next without physically moving either the glow lamp or the film.

Although the novel features which are believed to be characteristic of this invention will be more particularly pointed out in the claims appended hereto, the invention will be better understood by referring to the following description taken in connection with the accompanying drawing, in which a specific embodiment of the invention has been set forth for purposes of illustration, and in which:

Fig. 1 is an elevation of a glow lamp embodying the invention;

Fig. 2 is a front elevation of the glow lamp elements with the glass envelope removed;

Fig. 3 is a vertical section through the glow lamp elements;

Fig. 4 is a top plan view thereof;

Fig. 5 is a section taken on line 5—5 of Fig. 2;

Fig. 6 is a section taken on line 6—6 of Fig. 2; and

Fig. 7 is a diagrammatic view illustrating a sound recording system employing my improved glow lamp.

In the drawing, the invention is shown as applied to a glow lamp comprising an envelope 1 formed of glass or the like, carried by a base 2 having a plurality of connector prongs 3, 4 and 5 which are adapted to be inserted in a standard socket. The base 2 carries a support 6 of glass or the like by which the elements to be described are supported.

The elements of the glow lamp comprise an insulating block 10 formed of refractory insulating material such as lava and having at one side a V-shaped groove 11 in which a V-shaped cathode 12 is mounted. This cathode 12 may be made from a tantalum sheet having a thickness of about

.006" which is bent into the form of a V having an opening of about $\frac{1}{8}$ ".

An anode plate 14 is positioned over the front of the block 10 and is separated from the cathode 12 by means of a layer of insulating material 15 such as isinglass, mica or the like. The anode plate 14 has a pair of side flanges 16 which extend around the sides of the block 10 and are seated in suitable recesses 17 therein so as to form a shield for the light rays. The anode plate 14 is provided with an elongated aperture 18 which may for example have a width of .007" and may have a length of about 1", the length depending upon the width of the film to be scanned. The insulating material 15 is provided with a similar aperture 19 which may be substantially larger than the aperture 18 so as not to interfere with the passage of light rays therethrough.

The block 10 may be supported in any suitable manner. In the form shown this block is supported by a pair of vertical rods 20 and 21 which are connected respectively to posts 22 and 23, mounted in the glass support 6 and connected by leads 24 and 25 respectively to prongs 5 and 3. The rods 20 and 21 are positioned in suitable recesses 27 and 28 extending vertically along the sides of the block 10.

The rod 21 is extended over the top of the block 10 to connect with an ear 29 formed on the top of the anode plate 14. A support 30 may be extended across the bottom of the anode plate 14 and may be bent rearwardly at the side of the block 10 to engage the lower end of the rod 21.

The rod 20 is extended over the top of the block 10 and is provided with a downward extension 31 which enters the aperture within the V-shaped cathode 12 and extends downwardly to a point above the upper end of the aperture 18. This extension 31 is out of engagement with both the anode plate 14 and the cathode 12 and forms an auxiliary anode for a purpose hereinafter described.

The prong 4 is connected by means of a lead 32 to a pin 33 which is carried by the glass support 6 and is secured to the lower end of the V-shaped cathode 12.

In the lamp thus far described the glow discharge takes place between the V-shaped cathode 12 and the anode plate 14 to produce a light of uniform intensity throughout the entire length of the elements. This light passes through the aperture 18 and thereafter may be focussed on the film to be scanned. The auxiliary anode 31 is adapted to apply a fixed voltage to the lamp so as to prevent the discharge from being extinguished.

when a loud passage or blasting occurs, thereby tending to prevent distortion and to improve the operation of the lamp. The envelope may be filled with argon and nitrogen, or with other suitable gas so as to intensify the blue color spectrum which is particularly suitable for recording on standard photographic films.

In the system shown in Fig. 7 the glow lamp is shown connected to the output circuit of an amplifier 40, the input circuit of which is connected to a microphone 41. It is to be understood that the microphone 41 represents any suitable sound pickup device such as a mechanical pickup for disc phonograph records, a photoelectric pickup device 15 or the output of any audio frequency circuit. The output circuit of the amplifier 40 may include a battery 42 which may, for example, supply a potential of 600 volts between the anode plate 14 and the cathode 12. The auxiliary anode 31 may be connected to the anode plate 14 through a high resistance 44 such for example as a resistance of 100,000 to 500,000 ohms so as to supply a sufficiently high potential to the auxiliary anode to prevent the discharge from being extinguished 25 due to fluctuations in the main anode potential.

In accordance with this system the audio frequency currents received from the microphone or the like 41 are suitably amplified in the amplifier 40 and are impressed between the anode 30 and cathode of the glow lamp to cause a correspondingly fluctuating glow discharge therebetween. This glow discharge may be focussed across a film 50 by means of a cylindrical lens assembly 51 which is adapted to receive light 35 from the entire length of the aperture 18 and to focus the same in the form of a narrow beam extending across the entire active area of the film 50. An aperture plate 52 may be provided having an aperture 53 of a size to pass rays to a 40 selected sound record track only on the film 50. Suitable means may be provided for shifting the aperture plate 52 transversely of the film to progressively scan the successive sound record tracks.

It is to be noted that light of equal intensity 45 is supplied to all of the sound record tracks as the aperture plate 52 is shifted for scanning purposes. The system accordingly provides for successively scanning the various sound record tracks of the film without physically shifting

either the glow lamp or the film. Since the glow lamp remains stationary, distortion due to jarring the same by sudden movement is eliminated and the life of the glow lamp is materially increased. Furthermore a more accurate focussing can be 5 obtained because all of the elements remain at fixed distances, only the aperture plate 52 being movable. It is to be further noted that the aperture 18 is so narrow that the lamp may be placed comparatively close to the film. Consequently 10 the light loss due to dispersion of the light from the focussing point is maintained at a minimum.

It is to be understood that the lens assembly 51 could be made movable with the aperture plate 52 if desired, but in any event the glow lamp 15 would remain stationary throughout the scanning operation.

Although a particular embodiment of the invention has been shown and described for purposes of illustration, it is to be understood that 20 the invention is capable of various uses and it will be evident that various changes and modifications may be made therein as will be apparent to a person skilled in the art. The invention is only to be limited in accordance with 25 the following claims when interpreted in view of the prior art.

The invention claimed is:

1. A glow lamp comprising an elongated cathode of open V-shaped cross section, an anode 30 plate mounted across the open face of said cathode, said anode plate having an elongated aperture registering with said cathode to pass light therefrom in the form of a long narrow beam, and a second anode extending into the space 35 between said anode plate and cathode and insulated therefrom.

2. A glow lamp comprising a block of refractory insulating material, an elongated cathode of V-shaped cross section mounted in the face 40 of said block, an anode plate mounted across the face of said block and insulated from said cathode, said anode plate having an elongated aperture registering with said cathode to pass light therefrom in the form of a long narrow beam, 45 and a second anode carried by said block and extending within the space between said anode plate and said cathode and insulated therefrom.
